WOVEN TAPE

James A. Hendley, Middletown, Conn., assignor
to The Russell Manufacturing Company, Middletown, Conn., a corporation of Connecticut

Application June 28, 1939, Serial No. 281,586

2 Claims. (Cl. 139—383)

This invention relates to tape, and more particularly to tape which is primarily used as "zipper" tape.

One object of this invention is to provide an improved tape having elastic and inelastic portions extending side by side and so constructed as to minimize the likelihood of the elastic strands of the tape being cut or broken as a result of sewing operations on the inelastic portion of the tape.

Another object of this invention is to provide an improved tape having elastic and inelastic portions extending side by side and so constructed along the line of juncture of the elastic and inelastic portions as to have maximum neatness and uniformity of appearance.

Another object of this invention is to provide an improved tape having elastic and inelastic portions extending side by side, which can be readily manufactured to produce an attractive, durable construction at minimum cost.

With the above and other objects in view, as will appear to those skilled in the art from the present disclosure, this invention includes all features in the said disclosure which are novel over the prior art.

In the accompanying drawing in which one way of carrying out this invention is shown for illustrative purposes:

Fig. 1 is a perspective view of a fragment of tape made in accordance with the present invention;

Fig. 2 is a top-plan diagrammatic view of one form of weave that may be employed in the construction of the tape shown in Fig. 1;

Fig. 3 is a sectional view on line 3—3 of Fig. 2;

Fig. 4 is a perspective view similar to Fig. 1 after cords have been sewed along opposite sides of the inelastic portion of the tape;

Fig. 5 is a top-plan view of the tape shown in Fig. 4 with "zipper" elements mounted thereon; and

Fig. 6 is a sectional view on line 6—6 of Fig. 5. In the description and claims, the various parts are identified by specific names for convenience, but they are intended to be as generic in their application as the prior art will permit.

The particular form of tape 10 chosen for illustration in the drawing comprises an inelastic or non-elastic portion 11 and an elastic portion 12. The inelastic portion 11 has a first set of warp strands 13 of cotton or other suitable material, and the elastic portion 12 has a second set of warp strands 14 of

cotton or other suitable material. A pair of catch warp strands 15 of cotton or other suitable material extends back and forth across the set of warp strands 13 and 14. One or more inelastic weft strands 16 of cotton or other suitable material extends back and forth across the set for warp strands 13 and is looped around the furthest to the left of the warp strands 13 and around the pair of catch warp strands 15 as diagrammatically shown in Figs. 2 and 3. One or more elastic weft strands 17 extends back and forth across the set of warp strands 14 and is looped around the furthest to the right of the warp strands 14 and around the pair of catch warp strands 15. The elastic warp strand 17 is preferably composed of a vulcanized rubber strand covered with a winding of cotton or other suitable textile material, although any suitable elastic strand having elasticity similar to rubber may be used either with or without a suitable covering thereon. The broken line 15a, Figs. 1, 2 and 5, is used to indicate the general location of the pair of catch warp strands 15 between the inelastic portion 11 and the elastic portion 12.

Prior to using the tape 10 for mounting the "zipper" elements thereon, cords 18 and 19 of cotton or other suitable material are sewed along opposite sides of the non-elastic portion 11, as shown in Fig. 4. Then the "zipper" elements 20 are mounted on the tape 10 with the arms 21 and 22 of each "zipper" element clamping against the opposite side portions of the inelastic portion 11 and with the cords 18 and 19 engaged within the opening 23 of each "zipper" element 20. The cords ensure anchoring the "zipper" elements securely.

While one or more catch warp strands 15 could be used, I prefer to use two in order to accomplish a maximum neatness of appearance by avoiding the use of more than two, and minimizing the risk of damage to the tape by use of only one. More than two catch strands 15 would tend to be too bulky and cause too noticeable a ridge along the location of the strands 15. A single catch strand 15 would risk serious damage to the tape in the event that the single strand were to break and release the looped portions of the elastic weft strand 17, with consequent serious damage to the tape.

The invention may be carried out in other specific ways than those herein set forth without departing from the spirit and essential characteristics of the invention, and the present embodiments are, therefore, to be considered in all respects as illustrative and not restrictive, and all changes coming within the meaning and equiva-

lency range of the appended claims are intended to be embraced therein.

I claim:

1. A woven tape comprising: first and second sets of warp strands; one or more catch warp strands between said two sets of warp strands; an inelastic weft strand interwoven with said first set of warp strands and looped around said catch warp strands; and an elastic weft strand interwoven with said second set of warp strands and also looped around said catch warp strands but not interlocked with said inelastic weft strand.

2. A woven tape comprising: first and second sets of warp strands; a pair of catch warp strands between said two sets of warp strands; an inelastic weft strand interwoven with said first set of warp strands and looped around said catch warp strands; and an elastic weft strand interwoven with said second set of warp strands and also looped around said catch warp strands but not interlocked with said inelastic weft strand.

10

JAMES A. HENDLEY.
